McCaffrey & Flynn.

UNITED STATES PATENT OFFICE.

RICHARD J. DECY, OF JERSEY CITY, NEW JERSEY.

SHIPPING-PACKAGE.

1,388,804.

Specification of Letters Patent. Patented Aug. 23, 1921.

Application filed September 18, 1920. Serial No. 411,288.

To all whom it may concern:

Be it known that I, RICHARD J. DECY, a citizen of the United States of America, residing at Jersey City, New Jersey, have invented a new and useful Shipping-Package, of which the following is a specification.

My invention relates particularly to a package or container intended for shipping ice cream.

10 The main object is to provide a construction which can be made at a reasonable cost, which will have a maximum of strength with a minimum weight, and be capable of maintaining the contents at a low temperature 15 for a considerable period of time.

Great quantities of ice cream are shipped from the manufacturer to dealers, and it is necessary to maintain this cream in a solid, frozen condition for many hours. It has 20 been customary to pack the ice cream cans in containers with ice and salt. The expense of preparing the package in this way is considerable, and, furthermore, the brine leaking from these containers frequently 25 damages articles with which it comes in contact. Furthermore, the weight of the ice and salt materially adds to the shipping charges. The method at present employed in shipping ice cream produces a bulky 30 package, usually heaped up with ice and salt and covered with burlap, so that it is difficult, if not impossible, to stack the packages one on top of the other.

To overcome these disadvantages I have 35 designed a container which will be herein-after described in its preferred form.

The drawing shows a side view and partial vertical section of a construction embodying the improvements of my invention. 40 Preferably the outer part of the container or tub has a wooden bottom 1 and side wall 2, preferably formed of wooden staves, bound together with hoops, such as 3.

Inside is an auxiliary bottom 4, preferably 45 of wood, supported above the bottom 1, and the space between the two bottoms is filled with some suitable insulating material, such as cork 5.

Inside is another wall 6, preferably 50 of metal, supported on the bottom 4 and spaced apart from the outer wall. The space between the two vertical walls is preferably filled with insulating material, such as cork 7. The wall 6 may be fastened by a cleat 6'.

55 The upper end of the wall 6 is preferably flanged over onto a collar 8, which may be

formed of wood and inserted between the walls 6 and 2. The bottom 4 and the collar 8 are preferably of material which has a low coefficient of conductivity, and they are 60 suitably held in place, for instance, by nails or screws such as 9 and 10.

A gasket 11 is preferably provided in a groove in the upper surface of the collar 8. This gasket is preferably in the form of a 65 yielding tube of rubber. The inner portion of the container is provided with a cover 12, which fits into the mouth of the wall 6 and has a flange which rests on the gasket 11 so as to provide an air-tight joint. 70

The ice cream is preferably contained in a can 13 of the usual type, having a cover 14.

The shipping container is provided with a cover having an outer wall 15 and an inner wall 16 with a space between, which 75 is preferably filled with insulating material, such as 17. The inner part of the cover fits inside the upper edge of the tub, and an outer flange 18 fits outside the upper edge. To hold the cover in place I may provide 80 a plurality of fastening devices, each of which has a hinged or swinging member 19, slotted at its lower end to receive an eyebolt 20. In the position shown in the drawing a cord, wire or chain may be run through 85 these eye-bolts and sealed for shipment. To release the cover each eye-bolt is turned so that the fastening member 19 may be released.

For additional insulating purposes a layer 90 or disk 21 of insulating material, such as felt or hair, may be interposed between the inner and outer covers of the shipping container. If desired, one or more spring clips, such as 22, may be interposed between the 95 ice cream can 13 and the inner wall of the container, to prevent the can from shifting. Ordinarily, however, the ice cream can will fit rather snugly inside of the inner wall of the container. 100

The shipping container is preferably provided with one or more handles, such as 23, for convenience in moving the container.

This invention has been tested and found to be sanitary and to maintain the contents 105 in good condition for many hours without the use of ice or salt. The structure is sufficiently rugged to withstand hard usage in transportation for a long time. As the package is flat on the top as well as on the 110 bottom, it is possible to stack such packages and thus take up a minimum of space.

The insulating material in this construction is much lighter than the amount of ice and salt which would be necessary in an ordinary package, so that my package may be 5 shipped much more cheaply than the usual construction.

I claim:

1. A shipping package for ice cream, etc., comprising a tub having inner and outer 10 walls with insulating material between said walls, an inner cover and gasket for hermetically sealing the inner wall, and an insulating cover fitting the upper edge of the outer wall.
- 15 2. A shipping container for ice cream, etc., comprising a tub formed of wood and having bottom and a side wall, an interior bottom, insulating material between the said inner bottom and the bottom of the tub, an 20 inner wall, insulating material between the inner wall and the side wall of the tub, an insulating collar, a cover fitting said collar and the inner wall, and an outer cover fit-

ting inside and outside of the side wall of said tub.

25

3. A shipping container comprising an outer wooden tub, an inner metallic lining rigidly secured therein, insulating material between said tub and said lining, a tight cover for said lining, a flat cover for said 30 tub, and insulating material between said covers.

30

4. A shipping container comprising an outer tub, an inner lining, an insulating bottom for supporting said lining, an insulating collar supporting the upper end of said lining, insulating material between said lining and said tub, a cover for said lining, and a cover for said tub including insulating 35 material.

40

5. An iceless container comprising a tub, a lining, a wooden collar supporting the upper edge of the lining, insulating material between said tub and said lining, and an air-tight insulating cover for said tub.

45

RICHARD J. DECY.
